UNITED STATES PATENT OFFICE

157,581

CHARM OR SIMILAR ARTICLE

Estelle Frank, New York, N. Y.

Application October 22, 1949, Serial No. 5,653

Term of patent 7 years

(Cl. D45—17)

To all whom it may concern:

Be it known that I, Estelle Frank, a citizen of the United States, residing at New York, in the county of New York and State of New York, have invented a new, original, and ornamental Design for a Charm or Similar Article, of which the following is a specification, reference being had to the accompanying drawing, forming part thereof.

In the drawing

Fig. 1 is a front elevational view of a charm showing my new design;

Fig. 2 is a rear elevational view thereof; and Fig. 3 is a side elevational view thereof.

I claim:

The ornamental design for a charm or similar article, substantially as shown.

ESTELLE FRANK.
